Mark O. Uitz, Mountain View, Calif., assignor to F. J. L. Corporation, Palo Alto, Calif., a corporation of California

Filed May 8, 1969, Ser. No. 17,074

Term of patent 14 years

Int. Cl. D6—01

U.S. Cl. D33—31

FIG. 1 is a perspective view of a toilet paper holder embodying my new design;

FIG. 2 is a top plan view thereof;

FIG. 3 is an elevational view taken from the right end thereof;

FIG. 4 is an elevational view taken from the left end thereof; and

FIG. 5 is a front elevational view thereof.

The broken line representation of a toilet paper roll in FIG. 1 and the fragmentary broken line representation of a wall and support member in FIGS. 2, 3 and 4 are for purposes of illustration only.

I claim:

The ornamental design for a toilet paper holder, as shown and described.
